AUTOMATIC DOOR OPERATING
MECHANISM

August P. Konter, Cleveland, Ohio

Application November 28, 1932, Serial No. 644,634

5 Claims. (Cl. 268—63)

This invention relates to automatic door operating mechanism, and more particularly to mechanism of this nature adapted to be used for different types of doors such as hinged doors, sliding doors or overhead doors. The principal object of the invention is to provide a safe and reliable operating unit which can readily be installed above or at the side of the door, either angularly related thereto or parallel therewith and which includes a relatively small non-reversible electric motor for opening and closing the doors, a further object of the invention is to provide such unit with a traveling head or carriage adapted to be connected to the doors to be operated upon, which head is guided in a track, forming the frame of the unit and is provided with switching means for controlling the motor of the unit, to stop the traveling head at predetermined positions, when the doors connected therewith have reached fully closed or open position. A still further object of the invention is to provide a door operating unit with an endless chain drive coupled with the traveling head, which chain drive embodies operating means for switching means controlling the motor of the unit whereby these operating means may be readily adjusted with respect to the chain drive.

With the foregoing and other objects in view which will more readily be understood as the description proceeds, the invention consists in the combination of parts described and claimed in the following specification, and illustrated in the accompanying drawings, wherein:

Figure 1 is a plan view of the operating unit according to the invention;

Figure 2 is a side view of the operating unit shown in Figure 1;

Figure 3 is a diagrammatic view of the wiring system, showing the several points of control;

Figure 4 is a cross sectional view on line 4—4 of Figure 1;

Figure 5 is a cross sectional view on line 5—5 of Figure 1;

Figure 6 is a longitudinal fragmentary sectional view on line 6—6 of Figure 5;

Figure 7 is a cross sectional view on line 7—7 of Figure 1;

Figure 8 is a longitudinal fragmentary sectional view on line 8—8 of Figure 7;

Figure 9 is a cross sectional view on line 9—9 of Figure 1;

Figure 10 is a cross sectional view on line 10—10 of Figure 1; and

Figure 11 is a diagrammatic view showing the

doors of a double garage hooked up with the operating unit for selective or joint operation of the doors; and

Figure 12 is a diagrammatic view of the hook up of the doors of a single garage with the operating unit.

Referring to the drawings A represents a door operating unit embodying two oppositely arranged channel irons 2, secured in spaced parallel relationship to each other, and provided with upper and lower flanges 3 and 4, respectively. An angle iron 5, attached by means of bolts 6 to the upper flanges 3 of channels 2 connects the outer ends of said channels together, and a motor supporting platform 7, provided with laterally extending attaching arms 8, bolted to the depending web portions of said channels, connects the inner or opposite ends of channel irons 2 together. Channel irons 2 may be secured to the ceiling by any suitable means, not shown. The unit also includes a carriage or traveling head 10 which reciprocates on the lower flanges 4 of channel irons 2 when the unit is being operated. Traveling head 10 comprises a rectangular base plate 11 pivotally supporting at its four corners grooved rollers 12 which have free rolling engagement with the edges of the lower flanges 4 of channels 2, and thus efficiently guiding the head and preventing same from tilting and binding. Plate 11 carries a short shaft 12' fixed thereto by means of angular brackets 13, in turn secured to the bottom of said plate by bolts 14. Suitably connected to the shaft 12' is a connecting rod 15 adapted to be attached to one or more doors D by means of links 15'. Connecting rod 15 extends slidably through a small opening 12" in shaft 12' and is yieldingly held against axial movement with respect to the shaft by compression springs 16, 16' sleeved upon said rod and seated at their respective outer ends against a collar 17 and a nut 18 on said rod, the inner ends of the springs being seated against the shaft.

The carriage 10 is driven from a nonreversible motor 19, by means of an endless sprocket chain 20, the respective flights of which are confined between channel irons 2. This chain meshes with a drive sprocket 21 and an idle sprocket 22, supported at opposite ends of the channel irons 2, by plates or brackets 23 and 24, in which the respective vertically disposed sprocket shafts 25 and 26 are rotatably mounted. Thus shaft 25 is rotatably mounted in a bearing 27 rigidly connected to a plate 23 by means of screws 28. Bracket 23 in turn being rigidly attached to the upper flanges 3 of channels 2 by means of bolts 110

28'. Shaft 26 is pivotally mounted in a bearing 29 secured to a plate 24 by means of a screw 30 and bracket 24 is slidably clamped to the flanges 3 by means of strips 24' and bolts 24'', thus 5 making it possible to place chain 20 under tension by means of a hook shaped screw bolt 31 extended through a perforation 32 in angle iron 5. Mounted on the free end of shaft 25 is a large pulley 33 driven by a V-shaped belt 34' which 10 connects pulley 33 with a small pulley 34 fixed to a shaft 35. This shaft 35 is rotatably mounted at its lower end on a bracket or plate 36 and at its opposite end is secured to an angularly shaped strap 37, in turn attached to said bracket by 15 bolts 37', which bolts also secure the plate 36 to the upper flanges 3 of channel members 2. A large pulley 38 mounted on the lower end of shaft 35 is operatively connected with a small pulley 39 on motor shaft 40, by means of a second V shaped belt 38'.

23 Sprockets 21 and 22 and chain 20 are continuously driven in one direction by the nonreversible motor, whereas it is necessary that the carriage 10 have reciprocal movement on its track 4. This is accomplished by providing one of the links 41 of the chain 20 with a downwardly projecting pin 42, which pivotally engages with a sleeve member 43, adapted to slide transversely upon a rod 44 mounted on plate 11 by means of brackets 45.

35 When the pin 42 reaches and is about to turn with one of the sprockets 21 or 22, the doors D will have been either fully opened or fully closed, by the movement of plate 10, connecting rod 15 and links 15'. Consequently it is necessary that the motor be automatically stopped and travel of plate 10 halted when the doors have reached their limit of movement. This is effected when a lug 49 connected to one of the links of sprocket 40 chain 20 reaches and actuates one of two switches 47, 48, mounted on the inner side of end wall 57 of a box 50, to open motor circuit 46. Switches 47, 48 are connected with the respective levers 51 and 52, by means of switch operating arms 45 and links 54. Levers 51 and 52 are pivotally connected at their ends 55 to plates or brackets 56, depending from the end walls 57 of box 50, the pivotal connections of said levers being laterally offset with respect to said switch members 50 to permit automatic closing of said switches by gravity. The free ends 58 of levers 52 support horizontally arranged rods 59 adapted to be engaged with and be lifted by the lug member 49, when a roller 61 on the lug member engages a bent up portion 60 on one end of rods 59, which movement is communicated to the switches 47 or 48. A second roller 62 on lug member 49, rides upon a short guide rail 63 on channel iron 2 as the switches are reached, thus insuring positive contact between the roller 61 and rod 59. The latter is held in elevated position until roller 62 passes over the guide rail 63, whereupon the free ends of levers 52, 52' will be free to drop by gravity, to close one of switches 47, 48.

65 The operation of the device will be readily understood in connection with the showing of the illustrated circuit. In the normal position of the parts when the carriage 10 completes one leg of its reciprocal movement and the doors D operated thereby are substantially fully opened or closed, the circuit is interrupted by one of the switch members 47, 48 which latter is moved to and held in open position by lug member 49.

To close the motor circuit the operator actuates 55 either of a plurality of push button switches 64,

65 or 66. Assuming for example switch 66 has been operated, then current will flow from power line a through switch 66 into line b to and through fuse box 67 and motor 19 to grounded line c. After chain 20 has traveled for a short distance the lug member 49 which holds one of the switch members 47 or 48 open, will become disengaged from the horizontal rod 59 of the respective switch member and thus permit closing of said switch member by gravity. With both switches 47 and 48 thus closed the circuit remains closed even when push button 66 is released. Therefore carriage 10 will continue its travel until it approaches the opposite end of its reciprocatory travel and until lug member 49 engages with the corresponding horizontal rod 59 of the other of switch members 47, 48, and thus interrupts the circuit. The relative location of parts is such that lug 49 will open the circuit before carriage 10 reaches the end of its movement, and while motor 19 is coming to a stop. The described arrangement can be operated with a simple nonreversible motor, without the necessity of providing means for braking the motor after the current has been cut off. The position of lug 49 on chain 20 can be readily adjusted by attaching said lug to any one of a series of apertured ears 66, by bolts 67 (see Figures 1 and 7), to time the interruption of the line with respect to the movements of carriage 10.

100 Rod 59 may be bent up or cut off to compensate for the normal idling movement of the motor after either switch 47 or 48 has been opened.

105 The operating unit may also be used for operating a double garage having two hinged doors 110 69; see Figure 11, in which the reciprocatory carriage 10 of said unit is coupled with the two hinged doors of the garage by means of two connecting rods 70. If desired one of rods 15' may be disconnected so that only one door is operated. 115

115 It is preferably desirable to provide means for switching on a light positioned above the door or at any other desirable location, when the door is opened. In Figure 3, I have illustrated a lighting circuit 70 adapted to be opened and closed by 120 three way switch 47.

125 Having thus described my invention: What I claim is:

1. A door operating unit for opening and closing a door, comprising a pair of tracks, a carriage riding on said tracks, an endless chain connected with said carriage for reciprocatory movement thereof, a non-reversible motor in driving connection with said chain, an electric circuit for said motor, two automatically closed switching means connected in series in said circuit, means bridging said tracks between their opposite ends and connected therewith for supporting said switching means, a gravity actuated lever system for automatically closing each of said switching means, horizontally and vertically shiftable means attached to said chain for co-operation with said lever system and means for vertically shifting said latter means for automatically opening and holding either of said switches open, when said chain travels predetermined distances. 135

2. A door operating unit for opening and closing a door, comprising a pair of tracks, a carriage riding on said tracks, an endless chain pivotally and slidably connected with said carriage for reciprocatory movement thereof, a non-reversible motor in driving connection with said chain, an electric circuit for said motor, two automatically closed switching means mounted 140

- on said tracks connected in series in said circuit, each of said switching means embodying a switch and a lever system for actuating said switch, means arranged between the opposite ends of 5 said tracks for supporting said switching means, vertically shiftable means connected to said chain and cooperating with said lever systems for automatically opening either of said switches when said chain travels predetermined distances 10 and holding said switches open, while said chain continues to travel a predetermined distance, and means on said tracks for vertically shifting said latter means for switching operations. 15
3. A door operating unit for opening and closing a door including an endless chain, a nonreversible motor for driving said chain, a circuit for controlling said motor, and means for automatically opening said circuit when said chain travels a predetermined distance and holding the 20 switch open while the chain continues to travel a predetermined distance, said means including vertically shiftable means coupled with said chain, switching means connected in series in said circuit, and pivotally supported lever systems, embodying horizontal rods adapted to contact with and to be shifted and held in shifted position by said vertically shiftable means. 25
4. A door operating unit for opening and closing a door comprising a pair of parallel tracks 30 connected at opposite ends with each other, a carriage riding on said tracks, a pair of sprocket wheels mounted on said tracks, an endless sprocket chain mounted on said wheels in driving connection with said carriage, a non-reversible motor in driving connection with one of the links of said sprocket chain, an electric circuit for said motor, gravity actuated switching means connected in series in said circuit for controlling same, supporting means for said switching means bridging and connecting said tracks between their opposite ends, a single means attached to another link of said chain for automatically opening either one of said switching means, and means for automatically shifting said single opening means vertically to effect opening of said switching means at predetermined points and for a predetermined length in the travel of the chain. 35
5. In a door operating unit including an endless chain, a nonreversible motor for driving said chain, and a circuit for controlling said motor, switching means for opening and closing said circuit, vertically shiftable means coupled with said chain and travelling therewith for controlling said switching means and stationary cam means for vertically shifting said vertically shiftable means and holding same in shifted position, while said chain travels through a predetermined distance. 40
